Attorney.

UNITED STATES PATENT OFFICE.

PIETRO DEFARNO, OF HURLEY, WISCONSIN.

COMBINATION CHAIR BED.

Application filed September 8, 1925. Serial No. 55,019.

The present invention relates to combination chair-beds and has for its primary object the provision of a convertible chair whereby the same may be readily arranged in the form of a bed when found desirable, the entire structure being compactly foldable when not in use.

Another very important object of the device is the provision of a foldable piece of furniture adapted for assuming the form of a chair, the bottom of which is extensible and the back of which is extensible.

Another very important object of the invention is the provision of a foldable piece of furniture adapted for assuming the form of a bed, the length of which may be adjusted.

A further important object of the invention is the provision of a foldable chair and bed structure that possesses great strength, and is comfortable and serviceable when not in use, the same being also easy and inexpensive to manufacture.

A still further important object of the invention is to provide a device of this nature which is exceedingly simple in its construction, efficient and reliable in use, easy to manipulate, not likely to easily become out of order, attractive in appearance, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing—

Figure 1 is a top plan view of the structure showing the same arranged as a bed.

Fig. 2 is a side elevation thereof,

Fig. 3 is a side elevation thereof showing the structure arranged as a chair,

Fig. 4 is a transverse vertical section substantially on the line 4—4 of Fig. 2,

Fig. 5 is a perspective view of one of the leg supporting structures,

Fig. 6 is a perspective view of one of the extensible sides of the body frame, and

Fig. 7 is a perspective view of the auxiliary back frame.

Referring to the drawing in detail, it will be seen that the body frame 5 is U-shaped in formation and formed of angle iron. A canvas seat 6 or any other suitable serviceable,

flexible seat is stretched across the body frame, being held in place by twine 7 passing through openings in the frame and openings in the edges of the seat. Studs 8 are provided in the sides of the frame 5 adjacent the intermediate portion for pivotally receiving a leg supporting structure which will be specifically described hereinafter, and being here indicated generally by the letter A.

Extendible side bars 9 are associated with the frame 5, one with each side thereof. Each bar 9 is formed of angle iron, having the vertical portion thereof longitudinally slotted as at 10 and provided adjacent one end with an inwardly curved hooked extension 11 for engaging the under edge of the respective side of the frame 5.

A hinge leaf 12 is mounted on the upper portion thereof at the other end. A leg supporting structure B is pivotally engaged with the hinged ends of the bars 9. A back frame 13 is constructed of angle iron, and has hinge leaves 14 on its extremity pivotally engaged with hinge leaves 12 as is indicated at 15. A canvas or the like seat 16 is stretched between the bars 9 and the sides and intermediate portion of the frame 13 by means of twine 17. A leg supporting structure C is pivotally engaged with the frame 13 adjacent its intermediate portion. Chains 19 are attached to the frame 13 and are engageable with hooks 20 provided on the bars 9, so that the back frame 13 may be disposed in the same plane with the frame 5 or at an angle thereto to form a reclining couch or chair, as is indicated to advantage in Fig. 3.

An auxiliary back frame is indicated at 22 and the sides thereof are slotted as at 23. Bolts 24 from the sides of frame 13 pass through the slot 23. It is to be noted at this time that rivets or like elements 24 pass through the sides of the frame 5 and 160 through the slots. A canvas or the like sheet 25 is stretched across the frame 22 by means of twine 26.

It is apparent that the bars 9 may be adjusted in relation to the frame 5 and that the auxiliary frame 22 may be adjusted in relation to the frame 13.

Particular attention is now directed to the leg supporting structures A, B and C, which are practically identical in construction, so that a description of one will suffice for all three. The supporting structure

- A. includes a base plate 27 having legs 28 rising from the end thereof and terminating in loops 29 merging into extensions 30 disposed transversely of the legs for abutting the sides of the frame 5. These leg supporting structures, when the extensions 30 abut the frame, are inclined so as to prevent their accidental swinging to a folded position when the chair-bed is in use.
- 10 The construction, operation, and utility, as well as the advantages of this invention will now be clearly understood without a more detailed description thereof. It is desired, however, to point out I designed the present structure particularly for use by automobile tourists, as the structure is very useful as a bed, reclining couch, and furthermore, is capable of being compactly folded in order that it will not take up much 20 room in the automobile when not in use.
- Of course, the device is capable of different other and desirable usages which I need not enumerate herein. The present embodiment of the invention has been disclosed 25 in detail merely by way of example since in actual practice it attains the features of advantage enumerated as desirable in the statement of the invention and the above description. It will be apparent that numerous 30 changes in the details of construction, and in the materials, in the sizes, and in the combination and arrangement of the parts

may be resorted to without departing from the spirit or scope of the invention as hereinafter claimed, or sacrificing any of its advantages. 35

Having thus described my invention, what I claim as new is:—

1. A combination chair-bed including, in combination, a bottom frame, bars slidably mounted on the bottom frame, a main back frame hinged to the bars, an auxiliary back frame slidably mounted on the main back frame, leg supporting structures, one hinged to the bottom frame, one hinged to the bars, one hinged to the main back frame, each leg supporting structure including a base plate, legs rising at an incline from the base plate and terminating in loops merging into extensions disposed transversely to the legs. 40
2. A combination chair-bed including, in combination, a bottom frame, bars slidably mounted on the sides of the frame, a back frame hinged to the bars, leg supporting structures, one hinged to the bottom frame, one hinged to the bars, and one hinged to the back frame, each leg supporting structure including a base plate having a pair of legs rising on an incline therefrom and terminating in loops merging into extensions 45 50 55 disposed transversely to the legs.

In testimony whereof I affix my signature.

PIETRO DEFARNO.
